sylvania

Application May 28, 1942, Serial No. 444,842

10 Claims. (Cl. 108—8)

This invention relates to roofing of shingles and particularly of shingles laid so as to have the appearance of shingles shaped and applied according to the American method.

The object of the invention is to provide a roofing giving greater economy in material and in application and less in weight while maintaining the same protection against the weather and offering a pleasing design of rectangular shingles laid according to the American method.

Fig. 1 shows a plan view of one form of shingle illustrating one embodiment of the unit forming the roof of our invention;

Fig. 2 is a plan view of a starter shingle;

Fig. 3 is a perspective view of a roof with the shingles laid;

Fig. 4 is a diagrammatic sketch of Fig. 1 showing with lines indicating the relation of the shingles when laid;

Fig. 5 is a perspective view of another form of roof embodying our invention;

Fig. 6 is a diagrammatic sketch of the shingle of the roofing of Fig. 5 with lines indicating the relation of the shingles when laid;

Fig. 7 is a plan view of another form of shingle as cut from a blank;

Fig. 8 is a perspective view of a roof with the shingles of Fig. 7 laid; and

Fig. 9 is a perspective view of another form of roof embodying our invention.

Fig. 1 shows a shingle A of asbestos cement material preferably having its exposed surface molded to imitate weathered wood or the like. The lower edge of the shingle has cut-outs 17 of unequal length and at these cut-out edges the butt is cut with raised lines 18 to give the finished roof a small individual shingle effect. One side 19 of the shingle A is shorter than the other side 20. At the top from the right edge 20 upward is a short diagonal 21 and from the left edge 19 downward a diagonal 22 of the same length is cut, the remainder of the top edge being a long diagonal 23 from the lower end 24 of diagonal 22 to the upper end 25 of diagonal 21.

In laying the shingles the entire roof is covered with an asphalt-saturated felt. A cant strip 26 is nailed at the eaves, then the starter course is laid down. Taking a starter shingle A' as shown in Fig. 2, similar to shingle A in shape but flat and shorter in height as indicated, one sixth of the starter shingles is cut off the right end as indicated by the line a and this one sixth section, designated 10a, is nailed to the lower left corner of the roof overhanging the eaves one inch. Succeeding full-size starter shingles A' designated

10b, 10c, etc., are nailed end to end along the edge of the roof similarly overhanging the eaves one inch. Minimum clearances 27 of one sixteenth of an inch are provided between these starter shingles.

The first full-sized shingle A, designated 11a in Fig. 3 of the first shingle course, is nailed flush over the starter course as shown. As the first starter shingle 10a is a section of one sixth of a full length of a shingle, there is a stagger between the starter course intervals and the first shingle course intervals. The second shingle 11b of the first shingle course is laid next to shingle 11a and flush with the starter course at its lower edge and the succeeding shingles 11c, etc., are similarly laid.

To start the second shingle course one-sixth is cut off the left end of the first shingle 11a and the other five-sixths is laid at the edge of the roof. The succeeding shingles 12b, 12c, etc., are laid in the same manner as 11b and 11c of the first shingle course. The one-sixth off the left end of shingle 11a staggers the intervals of the second shingle course in relation to the first shingle course as the first shingle course is staggered in relation to the starter course.

The overlap 29 of the second shingle course partially covers the first shingle course and the starter course leaving an area 28 of the first shingle course exposed. The triple layer area where the second course overlaps the starter course is headlap 30. One-third of the left end is cut off first shingle 13a of the third shingle course, so that this course will be staggered in relation to the second shingle course. Shingle 13a is nailed at the edge of the roof and shingles 13b, 13c, etc., are applied successively as the remaining shingles are in the first and second shingle courses. The third shingle course overlaps the second shingle course, leaving an exposed surface. The third shingle course overlaps the first shingle course, giving another headlap 30 of two inches.

The first shingle 14a of the fourth shingle course is cut in half and the right half is applied to the edge of the roof over the third shingle course. The remaining shingles 14b, 14c, etc., are applied successively as in the lower course. The overlap 29, the headlap 30 and the stagger 31 are the same as below. Two-thirds is cut from the left end of shingle 15a, the first shingle of the fifth shingle course, the remaining one-third being applied to the edge of the roof over the fourth shingle course. The succeeding shingles are applied as in the lower courses and stagger 31, over-

lap 28 and headlap 30 are the same. The rest of the roof is finished in a similar manner.

Shingle 13b is taken as representative of the shingles on the roof. Shingle 13b is shown in Fig. 4 in a diagrammatic sketch to show the stagger, overlap and headlap. In the lower left corner; area G represents the headlap between the apex of shingle 11a, right side of shingle 12a and the lower left corner of shingle 13b. Area H represents the headlap between the apex of a shingle 11a, the left side of shingle 12b and the lower left corner of shingle 13b. Area I represents the headlap between the right side of the apex of shingle 12a, the lower left corner of shingle 14b and the left side of shingle 13b. Area J represents the headlap between the left side of the apex of shingle 12b, the lower left corner of shingle 14c and the right side of shingle 13b. Areas K and L represent the headlap between the apex of shingle 13b, the lower edge of shingle 15c and the right side of shingle 14b and the left side of shingle 14c, respectively. Thus the headlap is separated into three pairs of areas. Area O represents the double lap of shingle 13b over shingles 12a and 12b. Area N represents the double lap of shingles 14b and 14c over shingle 13b. Area M represents the area of a single layer of the center of shingle 13b spaced about the thickness of one shingle away from the roof deck. The space beneath shingle 13b in area M is protected from the weather on all sides by other shingles. The space under area M, therefore, forms an isolated air pocket.

A roof is laid by first putting down a course of starter shingles followed by a course of full-sized shingles completely covering the starter course. Over this first course is applied a second shingle course which leaves a part of the surface of the first course exposed. Over the second course is laid down a third course, leaving a portion of the second course exposed. The third course partially overlaps the first course. This area is the headlap. On the third row is laid a fourth row and so on until the roof is completed.

If the shingles were laid merely abutting instead of overlapping, the abutting edges would leave a space beneath the shingles. Through this space the ice, snow and rain could penetrate and cause a leak. The more the upper shingles overlap the lower shingles the less the possibility of a high wind blowing water under the upper shingle and over the top of the lower shingle.

For various reasons shingles are not side lapped. Where the shingles abut against each other there is a space between them. This joint between these edges makes this area the least protected on the roof. The water tends to seep between the abutting shingles. Therefore, the two shingles between which there is seepage must overlap the shingle below them sufficiently for the joint to be completely underlaid. This requires the lower shingle to extend under the upper shingle up to a point where a third shingle is placed over the joint. For purposes of safety and greatest protection, it is the practice to carry the bottom shingle under the middle shingle and under the third shingle, as well, for a short space, so that in part the bottom shingle is overlapped by the bottom shingle and the top shingle. This triple layer, known as headlap, gives a margin of safety. By means of this headlap the water that seeps through a joint between the middle shingles strikes the underlying shingle. It is not possible for the water to go over the top of the underlying shingle and reach the roof deck as

the underlying shingle extends under the joint between the middle shingles to a point where the joint between the middle shingles is covered by the top shingle. The principal effect of the headlap, therefore, is the prevention of leakage at the joint between the shingles. It is needed only at the joint. When using the rectangular shingles of the American method of roofing, however, it is customary to carry the headlap across the full width of the shingle.

One of the advantages of our invention is the elimination of unnecessary headlap by the diagonals 21, 22 and 23 on the top of the shingle. The diagonals 21 and 23 form an apex at 25. The stagger 31 of the intervals 27 and the overlap 28 is so positioned that the apex 25 goes directly beneath the joint 32 between the shingles of the course above. Thus the joint is underlaid for the necessary two inches of headlap. The diagonal 23 then cuts away the shingle so that the amount of underlying surface is at a minimum. For the purposes of protection an overlap of two inches of shingle 14b on shingle 13b and shingle 13b on shingle 12b is required. Through 24, therefore, is two inches above the lower edge of shingles 14b and 13b. Thus, instead of three areas extending across the entire shingle in bands the headlap is reduced to areas G, H, I, J, K and L. The material eliminated by diagonal 23 not only avoids the excess headlap but also reduces the amount of double lap to the areas shown at N and O on shingle 13b. Thus, instead of every shingle being overlaid and underlaid so that the roof is entirely covered with a double thickness, the areas represented by area M of shingle 13b are of a single thickness. This reduction of the amount of material in the shingle does not reduce its effectiveness. The double lap is necessary underneath the lower exposed edge of each shingle for a depth of two inches. This is obtained. The headlap is carried under the joint to the next superimposed course to a point where the joint is covered by another shingle. The areas of headlap G, H, I, J, K and L are positioned at two corners and on the sides of the shingle so that the three layers give the shingle strategic support. The hollow space beneath area M is protected from all exposed surfaces by at least two inches of double lap.

Figs. 5 and 6 show views of asbestos cement shingle B, another form of our invention. In this variation the right side 33 and the left side 34 are long and short, respectively as before. The lower edge has square cut-out 17 but the raised lines are omitted. The top is comprised of a single diagonal 35. The apex 36 occurs at the extreme right side of the shingle. The shingle B is laid on the roof by the same method as the shingle A, the difference being that since headlap 37 at the intervals 27 must be at least two inches, the greatest depth of headlap is more than two inches, since the apex 36 and intervals 27 do not coincide in this form.

Shingle 43b shown in diagrammatic sketch in Fig. 6 is taken as representative of the shingles in Fig. 5. Areas Q, R, S, T, U, V and W are areas of the headlap. Axes X and Y are areas of double lap. Area Z is an area of single thickness. The areas of headlap in 43b are positioned the same as in shingle 13b of Fig. 4 except that the shingle 41b underlays the very tip of the right corner of shingle 43b which is underlaid also by shingle 42b, giving headlap area S. Areas of double lap X and Y and single lap Z are similar in position to the areas of double and single lap in the shingle

13b. The areas of headlap are placed in the corners and on the side, giving support and protection where needed. The sloping diagonal 35 eliminates unnecessary headlap confining it to the joints and reduces the layers to the single thickness of area Z in the center of the shingle.

Figs. 7 and 8 show a view of a shingle of our invention in another form. This variation is similar to the shingle A shown in Figs. 1 to 4 in that the top edge is broken into three diagonals, two short and one long. However, the angles made by the diagonals in this form are further from the perpendicular. In this development the two shingles C and C' are trimmed from an asbestos blank 45, 24 inches square. Fig. 7 shows the relative position of the two shingles cut from the one blank 45. The blank 45 is cut in half along three diagonals 46, 47 and 48. These correspond to the diagonals 21, 22 and 23 in the shingle A of Figs. 1 to 4.

In this variation however the left edge of the bottom shingle C and the right edge of the top shingle C' shown in Fig. 7 are cut perpendicular to the straight edge of the blank 45 from the diagonals to the edge of the blank. This forms two sections 49 at the center of the edge on opposite sides. These sections 49 are considered trimming waste. As a result the short diagonals 46 of the bottom shingle C and 48 of the top shingle C' are truncated and straight edges 50 and 51 are formed.

In Fig. 8 as in Fig. 3 is shown a view of a roof with shingles laid. A starter course 10'a, 10'b, 10'c, etc., is shown over which is laid the first shingle course 11'a, 11'b, 11'c, etc. The first shingle course is flush with the starter course but there is a stagger between the starter course intervals and the first shingle course intervals. In starting the second shingle course 12'a, 12'b, 12'c, etc., one-fourth is cut from the left end of the shingle and the other three-fourths is laid at the edge of the roof. The succeeding shingles are laid in the same manner as the first shingle course. The second shingle course is staggered in relation to the first shingle course as the first shingle course is staggered in relation to the starter course.

The shingle C is laid on the roof by the same method as shingles A and B, the amount of headlap and overlap obtained is substantially the same in vertical dimension but the total area is slightly decreased. The angle of the diagonals 46, 47 and 48 is changed away from the perpendicular to the side edges, thus the angles made between diagonals 46, 47 and 48 are more acute. The more acute angles between diagonals 46, 47 and 48 permit cutting off part of the top left corner of the shingle C as shown by section 49 in Fig. 7 without reducing the minimum vertical dimension of the double layer. This leads to a reduction in the amount of material in the finished shingle and an appreciably lighter product is obtained thereby.

Fig. 9 shows a further modification of the shingle A. In this development the shingle is cut to increase the protection offered to the roof. The minimum overlap 52 of the exposed surface of a shingle when applied to a roof over the underlying shingle is greater than the minimum overlap provided by shingle A.

The area of exposed surface 29' and the dimensions of the headlap 30' are not decreased. The minimum overlap 52 of the exposed shingle 12'a over the next underlying shingle 11'a is determined by the distance 29', the shingles 12'a and 11'a are set apart and by the minimum vertical dimension 53 between the top edge and

the bottom edge of the underlying shingle 11'a. The closer the shingles 12'a and 11'a are placed together the less will be the exposed surface 29' and the greater the overlap 52. At the same time the minimum overlap 52 may be increased by increasing the height of the minimum vertical dimension 53 of the shingle 11'a. This increases the distance by which the underlying shingle 11'a may be overlapped.

When two shingles are cut from one blank the peak 54 of one shingle forms the recess 55 of the other shingle. In the modification of shingle A shown the shingle in Fig. 9 the angle made by the diagonal 23' with a perpendicular to the side edges of the shingle is decreased. This reduces the vertical dimension 56 between the peak 54 of the shingle and the recess 55 in relation to the minimum vertical dimension 53. As a result the minimum vertical dimension 53 is increased in relation to the vertical dimension 56 between the peak 54 and the recess 55. Thus headlap 30' may be maintained at two inches while the minimum overlap 52 is increased to three inches. At the same time the exposed surface 29' is reduced only one-half an inch.

We claim:

1. A roof of overlapping asbestos cement shingles each generally the shape of a trapezoid having its greater dimension horizontal in assembled position on the roof, the upper edge being diagonal to said lower edge and with the upper end portion of the diagonal overlapped by a plurality of shingle thicknesses, the area of overlapping between the shingles not necessary to protect the roof being eliminated by said diagonal upper edge, and being divided into an area of two layers and an area of three layers, the smallest dimension of said two layer area being greater than the largest dimension of said three layer area.

2. A roof of overlapping asbestos cement shingles each generally the shape of a trapezoid having its greater dimension horizontal in assembled position on the roof, the upper edge being diagonal to said lower edge and with the upper end portion of the diagonal overlapped by a plurality of shingle thicknesses, the area of overlapping between the shingles not necessary to protect the roof being eliminated by said diagonal upper edge, and being divided into an area of two layers and an area of three layers, the smallest dimension of said two layer area being greater than the largest dimension of said three layer area, and each shingle having cut out from its lower edge sections and having formed and set in its exposed surface on a roof a plurality of longitudinally extending lines raised above the surface, said cut out sections and raised lines being spaced to give an effect of small individual shingles.

3. A roof of overlapping asbestos cement shingles each generally the shape of a trapezoid having its greater dimensions horizontal in assembled position on the roof, the upper edge being composed of three diagonals to the lower edge and with the upper end portion of the diagonal overlapped by a plurality of shingle thicknesses, said diagonals forming angles with each other to give an inclined zig-zag upper edge, the area of overlapping between the shingles not necessary to protect the roof being eliminated by the incline of said zig-zag upper edge, and being divided into an area of two layers and an area of three layers, the smallest dimension of said two layer area being greater than the largest dimension of said three layer area.

4. A roof of a plurality of shingles of asbestos and Portland cement composition, each shingle being generally the shape of a trapezoid of greater horizontal length than vertical height and being greater in height at one point than at another so that the upper edge is inclined and composed of three diagonals to the lower edge and with the upper end portion of the diagonal overlapped by a plurality of shingle thicknesses, the area of overlapping between the shingles not necessary to protect the roof being eliminated by said diagonals of said upper edge, and being divided into an area of two layers and an area of three layers, the smallest dimension of said two layer area being greater than the largest dimension of said three layer area.

5. A rigid shingle of the character described adapted to be laid with similar shingles in overlapping courses which comprises an elongated main body portion defined by a longitudinally extending edge forming the lowermost portion of said shingle when laid in courses, a pair of substantially parallel, end-defining edges extending substantially perpendicular to said longitudinal edge, one of said end-defining edges being longer than the other, and a pair of upper edge portions extending for a short distance inwardly from each of said end-defining edges and inclined relative thereto, and an oblique upper edge portion extending between the inner ends of said first mentioned upper edge portions.

6. A rigid shingle of the character described adapted to be laid with similar shingles in overlapping courses which comprises an elongated main body portion defined by a longitudinally extending edge forming the lowermost portion of said shingle when laid in courses, a pair of substantially parallel, end-defining edges extending substantially perpendicular to said longitudinal edge, one of said end-defining edges being longer than the other but both being of sufficient length to extend into the area normally overlapped by a superimposed similar shingle, a first upper edge portion extending inwardly for a short distance from the end of the longer end-defining edge and inclined relative thereto, a second upper edge portion extending inwardly for a short distance from the end of the shorter end-defining edge and inclined relative thereto, and a third upper edge portion extending obliquely between the inner ends of said first and said second upper edge portions.

7. A rigid asbestos-cement shingle of the character described adapted to be laid with similar shingles in overlapping courses which comprises

an elongated main body portion having the butt edge of the shingle extending longitudinally thereof and having end edges substantially perpendicular to said butt edge, said shingle having a generally tapered shape being wider at one end edge than at the other end edge and with the upper edge formed as a straight inclined line.

8. A rigid asbestos-cement shingle of the character described adapted to be laid with similar shingles in overlapping courses which comprises an elongated main body portion having a lower butt edge extending longitudinally of said body portion and having end edges substantially perpendicular to said butt edge, said shingle also having a generally tapered shape being wider at one end edge than at the other end edge and with the upper edge formed as a zig-zag line with parallel end inclines and an intermediate diagonal joining them.

20 9. A plurality of rigid shingles assembled in courses to form a roof covering, each of said shingles comprising an elongated main body portion having one longitudinal edge serving as the lower butt of said shingle, a pair of end edges 25 extending substantially perpendicular thereto, one of said end edges being longer than the other, and a generally obliquely extending upper edge between said end edges whereby a shingle is formed which is wider at one end edge than at 30 the other end edge, said upper edge comprising a series of zig-zag inclined portions.

10. A rigid shingle of the character described adapted to be laid with similar shingles in overlapping courses which comprises an elongated 35 main body portion defined by a longitudinally extending lateral edge forming the lowermost portion of said shingle when laid in courses, a pair of substantially parallel, end defining edges extending substantially perpendicular to said 40 longitudinal edge, one of said end defining edges being longer than the other, but both being of sufficient length to extend into the area normally overlapped by a superimposed course of shingles, a first upper edge portion extending inwardly for 45 a short distance from the end of the longer end defining edge, a second upper edge portion extending inwardly for a short distance from the end of the shorter end defining edge, and a third upper edge portion extending obliquely between 50 the inner ends of said first and said second upper edge portions so as to form a series of zig-zag inclined edges.

EDWARD J. BUCZKOWSKI.
STANLEY J. OSTROWSKI.
